Patented October 13, 1903.

UNITED STATES PATENT OFFICE.

EDWARD P. WAGGONER, OF SYRACUSE, NEW YORK, ASSIGNOR TO A. A. GRIFFING IRON COMPANY, OF JERSEY CITY, NEW JERSEY, A CORPORATION OF NEW JERSEY.

DESIGN FOR A RADIATOR.

SPECIFICATION forming part of Design No. 36,589, dated October 13, 1903.

Application filed August 29, 1901. Serial No. 73,761. Term of patent 14 years.

To all whom it may concern:

Be it known that I, EDWARD P. WAGGONER, of Syracuse, in the county of Onondaga and State of New York, have invented a new, 5 original, and ornamental Design for Radiators.

The accompanying drawing is a perspective of a radiator embodying my design.

What I claim is—

10 The ornamental design for a radiator, substantially as herein shown.

In testimony whereof I have hereunto signed my name, in the presence of two attesting witnesses, at Jersey City, in the county of Hudson, in the State of New Jersey, this 21st 15 day of August, 1901.

EDWARD P. WAGGONER.
